UNITED STATES PATENT OFFICE

105,473

DESIGN FOR A PICTURE FRAME

Manaloto Candido, Los Angeles, Calif.

Application August 1, 1936, Serial No. 64,171

Term of patent 3½ years

To all whom it may concern:

Be it known that I, Manaloto Candido, a citizen of the United States, residing at Los Angeles, in the county of Los Angeles and State of California, have invented a new, original, and ornamental Design for Picture Frames, of which the following is a specification, reference being had to the accompanying drawing, forming a part thereof.

Fig. 1 is a front elevational view of a picture frame showing my new design.

Fig. 2 is a vertical sectional view taken along the center of Fig. 1.

Fig. 3 is a horizontal sectional view taken along the center of Fig. 1.

I claim:

The ornamental design for a picture frame, as shown.

MANALOTO CANDIDO.
